UNITED STATES PATENT OFFICE

ARTHUR VON FRANKENBERG, OF NEW YORK, N. Y.

DESIGN FOR A STAND FOR AN ASH TRAY OR OTHER SIMILAR ARTICLE

Application filed September 12, 1931. Serial No. 41,079. Term of patent 7 years.

To all whom it may concern:

Be it known that I, ARTHUR VON FRANKENBERG, a citizen of the United States of America, and a resident of New York city, in the county and State of New York, have invented a new, original, and ornamental Design for a Stand for an Ash Tray or Other Similar Article, of which the following is a specification, reference being had to the accompanying drawing, forming part hereof.

The figure is a perspective view of my new design serving as a stand for an ash tray. It may also be used as a stand for a lamp, clock or other similar article.

I claim:

The ornamental design for a stand for an ash tray or other similar article, as described and shown.

ARTHUR VON FRANKENBERG.
